UNITED STATES PATENT OFFICE.

AGNES GILL, OF GENEVA, SWITZERLAND.

INVALID-MATTRESS.

1,199,886.

Specification of Letters Patent.

Patented Oct. 3, 1916.

Application filed December 17, 1915. Serial No. 67,439.

To all whom it may concern:

Be it known that I, AGNES GILL, a subject of Great Britain, residing at Geneva, Switzerland, have invented certain new and useful Improvements in Invalid-Mattresses; and I do hereby declare the following to be a full, clear, and exact description of the invention, such as will enable others skilled in the art to which it appertains to make and 10 use the same.

The invention relates to improvements in invalid mattresses.

The object of the present invention is to improve the construction of invalid mattresses and to provide a simple, practical and comparatively inexpensive construction designed for use on an ordinary bed and equipped with a commode opening to enable evacuations to occur without disturbing either the patient or the bed whereby the mattress is adapted for use in hospitals, and homes for the use of the sick as well as paralyzed or other bed-ridden persons.

With these and other objects in view the 25 invention consists in the construction and novel combination, and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

30 In the drawings Figure 1 is a sectional perspective view of an invalid mattress constructed in accordance with this invention, Fig. 2 is an enlarged sectional view through the commode opening showing the same closed by a removable cushion. Fig. 3 is a similar view, the cushion being removed and the porcelain sleeve and the stand being in position, Fig. 4 is a detail view of the metallic ring of the central section of the upper mattress, Fig. 5 is a similar view of the metallic ring of the spring mattress, Fig. 6 is a detail sectional view illustrating the manner of securing the lower ring to the spring mattress, Fig. 7 is a detail sectional view 45 illustrating the construction of the commode stand. Fig. 8 is a detail perspective view of the metallic lining.

Like numerals of reference designate corresponding parts in the several figures of 50 the drawings.

In the accompanying drawings in which

is illustrated the preferred embodiment of the invention, 1 designates an upper mattress of hair or other suitable material preferably composed of central and end sections 2 and 3, the central section being provided with a commode opening located at the center of the mattress and provided with a lining 4 of waterproof or other suitable material and receiving a removable cushion, 5 which closes the opening when the commode stand 6 is not in use.

The removable cushion 5 may be of any desired construction and is designed to be filled with hair, felt, or other material of which the mattress 1 is constructed.

The mattress 1 is arranged upon a spring mattress 7 of any desired construction provided with a central metallic ring 8 having upstanding lugs 9 adapted to engage the central section 2 of the mattress 1 to prevent the same from slipping and carrying its commode opening out of alignment with the central opening of the lower support or spring mattress 7. The ring 8 of the lower support or spring mattress 7 may be secured to the wire thereof in any suitable manner preferably by means of a flange 10 as clearly illustrated in Fig. 6 of the drawings but any other suitable means may of course be employed for connecting the ring to the spring mattress.

The upper mattress is provided at the bottom of the commode opening with a metallic ring 11 provided with lugs 12 and having depending rings 13. The lugs or ears facilitate the attachment of the ring to the upper or main mattress and the said upper plate or ring is also provided at its lower face with the aligned rings or eyes 13 for the reception of the rod 14 which retains the cushion 5 in place and prevents the same from being forced downwardly and through the opening. The outwardly extending ears 12 are preferably arranged between the lining and the body of the upper mattress as clearly shown in Fig. 2 of the drawings.

When the cushion is removed the commode opening is adapted to receive a metallic sleeve 15 preferably enameled and provided at its upper face with a supporting means 16. The sleeve which is adapted to protect the mattress receives a receptacle 17 of the commode stand 6. While the supporting means is shown in the form of a tape any other means may of course be employed for retaining the metallic lining in

position in the opening of the central section 2. The tape will enable the metallic lining to be drawn up and lowered from its position and it may be secured to the bed in 5 any desired manner. The receptacle 17 is provided with a depending stem 18 which fits in a tubular portion 19 of the base 20 of the stand. The receptacle is adapted to be raised and lowered to extend it into the 10 commode opening and to withdraw it therefrom and it is secured in its adjustment by a removable pin 21 adapted to be arranged in perforations 22 and 23 of the stem and the tubular portion of the base but any other 15 suitable means may be employed for securing the commode stand in its adjustment. Instead of employing a commode stand any other form of commode may be used and in hospitals it may be used in connection with 20 a water closet having flushing means arranged within reach of the patient.

What is claimed is:—

1. A device of the class described including a mattress having a commode opening 25 and provided therewith a lining, a ring or plate surrounding the opening at the bottom of the mattress and provided with ears projecting from the outer periphery and

secured to the bottom of the mattress, said ring or plate being also provided with depending eyes, a removable cushion fitting in the commode opening and supporting rods arranged in the said eyes for holding the cushion in position. 30

2. A device of the class described including an upper mattress having a commode opening, a lower support having an opening registering with the said opening, a removable metallic sleeve fitted in the commode opening and provided with supporting 40 means and a commode stand having a receptacle fitting in the sleeve. 35

3. A device of the class described including a mattress having a commode opening and a metallic lining having flexible supporting means extending through the opening and adapted to permit the lining to be raised and lowered and introduced into the opening from beneath. 45

In testimony whereof I affix my signature 50 in presence of two witnesses.

AGNES GILL.
